BOTTLE OPENER

Fred W. Pollock, Eugene, Oreg., assignor of one-half to Frank M. Crabill, Eugene, Oreg.

Application December 1, 1934, Serial No. 755,593

2 Claims. (Cl. 65—46)

This invention relates to a bottle opener, one of the objects being to provide a device of this character which simulates a bottle in appearance and can be sold as an article for general use or can be distributed as an advertising novelty.

Another object of the invention is to provide an all metal device of this character which is formed of few parts and in which the portion employed for engaging a bottle cap is normally concealed, it being possible by slight longitudinal pressure on a part of the device, to bring the several parts into proper position for removing a bottle cap.

A still further object is to provide a bottle opener which is not only attractive in appearance but is also durable in construction, it being impossible for the parts to become accidentally separated except by breakage after the parts have once been assembled.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

30 In said drawings

Figure 1 is a side elevation of the device showing the parts in their normal positions.

Figure 2 is a vertical section through the structure with the parts located as in Figure 1.

35 Figure 3 is a view similar to Figure 2 showing the bottle opener shifted into cap-engaging position.

Figure 4 is a section on line 4—4 Figure 2.

40 Figure 5 is a section taken on the same line as Figure 4 but looking in the opposite direction, the hook being removed.

Figure 6 is a top plan view of the upper body portion shown in Figures 2 and 3.

45 Figure 7 is a bottom plan view of the lower body portion shown in said figures.

Figure 8 is a side elevation showing the two body portions assembled with the outer casing sections removed.

50 Figure 9 is a section on line 9—9 Figure 2.

Figure 10 is a section on line 10—10 Figure 2.

Figure 11 is a section on line 11—11 Figure 2.

The present device is made up of two inner or body members oppositely disposed and in sliding engagement with each other, an outer casing member covering each of the body members, a

cap, and a hook. Under some conditions an added part can be used, namely, a label portion.

Referring to the figures by characters of reference, 1 designates a body member formed of metal and shaped to provide a longitudinally extended channeled portion 2 having flat horizontal sides 3 along the free edges of which are formed laterally extended flanges 4. The flat side walls are flared at one end to form arcuate end flanges 6 angular in cross section, the outer curved surfaces of which merge into the arcuate end portion 7 of the channeled body 2 so as to form a substantially semi-circular recess indicated at 8. The other end of the body 1 can be tapered or otherwise shaped at 9 to simulate one-half of the neck and mouth portion of a bottle.

At a point between its ends the body is formed with a transverse depression 10 intersected by a short slot 11 and seated in this depression are laterally extended lugs 12 projecting from one end 20 of a shank 13. At the other end of this shank is a hook 14 and opposed end portions of the shank are disposed at an obtuse angle to each other so that it is thus possible to move the hook upwardly within the body 1 a sufficient distance to completely house it when all of the parts of the opener are in their normal positions. The angular form of the shank 13 also allows the hook to be extended in proper position for engaging a cap when the opener has been adjusted for that purpose.

30 The other body portion of this device has been indicated at 15 and includes a longitudinal channeled portion 16 having opposite extending side flanges 17. These flanges terminate at one end in arcuate flanges 18 angular in cross section, the curved outer faces thereof merging into the curved end portion 19 of the body 15 so as to form a substantially semi-circular recess 20 in said end of the body. The sides of the channeled portion 16 are flat and preferably parallel 40 as indicated at 21. At that end of the body remote from the recess 20 there is provided an extension 22 similar to the extension 9 so that when the two body portions 1 and 15 are assembled opposite each other and in contact so that the flanges 4 will rest on the flanges 17, the two extensions 9 and 22 will substantially simulate the neck and mouth portion of a bottle.

Longitudinal slits 23 are provided in the channeled portion 16 and extend thereinto from the 50 recessed end 19. The metal between these slits forms a supporting tongue or rest 24 which is inclined outwardly toward the plane of the flanges 17.

Each of the flanges 17 has a longitudinal side 55

wing 25 which is extended at right angles thereto and inwardly so that each wing, which is angular in cross section, thus overlies its flanges 17.

5 Mounted on the body 1 is an outer casing or shell 26 simulating one-half of a bottle and this shell has a semi-circular end portion 27 which is pressed into the recess 8 while at the opposite end of the shell there is provided a small tongue 28 adapted to be bent back into a notch 29 in the body 1. Thus the shell casing member 26 is fixedly secured to the body 1.

10 Another shell or casing member 29 simulating one-half of a bottle is mounted on the outer surface of body member 15 and has a semi-circular end portion 30 pressed into the recess 28 while at the other end of this shell or casing member there is a tongue 31 bent back into a notch 32 formed in the adjacent end of the extension 22 of body 15.

15 20 In assembling the parts of this device the hook is combined with the body portion 1, the shells are applied on the respective body portions, and said body portion 1 is then placed on the body portion 15 with the end 27 adjacent to the neck portion or extension 22 of the opposed section. Said body portion 1 is then slid longitudinally so as to move the end portion 27 toward the end portion 30 and away from the neck portion 22. This will cause the angular wings 25 to slide into 25 engagement with the flanges 4 as shown in Figures 9 and 10 and as soon as the small end of body portion 1 and its shell 26 have passed inwardly from the corresponding end of body portion 15 a cap 33 simulating an ordinary crown cap can 30 be soldered or otherwise fastened on the small end of shell 29 as shown in Figure 3. The body 1 and the parts carried thereby can then be slid back until the small end of shell 26 moves into the cap 33. This will bring the end portions 27 and 30 into alignment and the parts will assume 35 the positions shown in Figures 1 and 2 with hook 14 resting on and supported by the inclined tongue 24. With the parts thus located the device will have the appearance of a miniature bottle and 40 can be stood up on end.

45 Should it be desired to use the opener, the same is grasped in one hand and by means of the thumb the body 1 and the parts carried thereby are pushed away from the cap 33 until the wings 25 come against the end flanges 6. This will cause the hook 14 to ride off of the tongue 24 and move to the position shown in Figure 3. The large end of body 1 and its shell 26 can then be placed on the cap C to be removed 50 while hook 14 can be caught in the flange of said

5 cap (see Figure 3). The neck portion of the device can then be used as a handle and by pulling it upwardly as indicated by the arrow in said figure, the cap-engaging portion of shell 26 will act as a fulcrum and hook 14 will pull on the flange of the cap and disengage the cap from its bottle. After the device has been used the member 1 and its shell can be slid back into the position shown in Figures 1 and 2, thereby causing the hook to swing up into the body portion 1 and 10 assume the position shown in Figure 2.

15 Obviously after the parts have once been assembled and the cap 33 fastened in place it will not be possible to separate them and, therefore, there will be no danger of any of the parts becoming lost or misplaced.

20 If desired the representations of labels can be impressed on portions of the device or thin plates representing labels and bearing suitable data can be soldered or otherwise joined to one or both of the shells. Representations of these labels have been indicated at 34.

25 What is claimed is:

1. A bottle opener including opposed members 30 slidably connected and each including a flanged body and an outer shell mounted on the body, the shells cooperating to conceal the bodies when assembled, means on the flanges on one of the bodies and cooperating with the flanges of the other body for holding said bodies against separation when moved in one direction relative to each other, means carried by the shell on one of the bodies and cooperating with the shell on the other body for limiting the relative movement of the bodies in the opposite direction, a hook movably 35 connected to one of the bodies and normally housed between the bodies, said hook being shiftable to position outside of one of the bodies when the other body is moved in one direction relative to said body.

40 2. A bottle opener simulating a longitudinally split bottle and including slidably connected upper and lower portions, cooperating means thereon for holding said portions against separation while in use, one of said portions when shifted longitudinally relative to the other portion providing an end projecting beyond the end of the other portion for bearing upon a cap to be removed from a bottle, and a hook carried by said portion and normally housed within both portions, said hook being shiftable to hanging position under the projecting end of one member and across the end of the other member by said relative movement of the opposed portions.

45 50 55 FRED W. POLLOCK.
